H. BRINKHAUS.

EYEGLASSES.

APPLICATION FILED FEB. 29, 1916.

1,193,984.

Patented Aug. 8, 1916.

Inventor
Augs Brinkhaus
By his Attorney
Henry K. Williams

UNITED STATES PATENT OFFICE.

HUGO BRINKHAUS, OF BROOKLYN, NEW YORK.

EYEGLASSES.

1,193,984.

Specification of Letters Patent. Patented Aug. 8, 1916.

Application filed February 29, 1916. Serial No. 81,103.

To all whom it may concern:

Be it known that I, HUGO BRINKHAUS, a citizen of the United States, residing in the borough of Brooklyn, in the county of 5 Kings and State of New York, have invented certain new and useful Improvements in Eyeglasses, of which the following is a specification, reference being had therein to the accompanying drawings, forming 10 part thereof.

My invention relates to eyeglasses of the pince-nez type and is an improvement upon the invention disclosed in my application for patent for pince-nez filed August 3, 1915, 15 Serial No. 43,420.

Important objects of the present invention are to simplify the construction, decrease the cost of manufacture and improve the appearance of the pince-nez.

20 Other more particular objects and advantages of my invention will hereinafter appear.

In carrying out my former above noted invention, I employed a comparatively rigid 25 lens-supporting bridge piece and a separate transversely extending placket-carrying spring member, lever arms being connected to the plackets and pivoted upon the bridge piece for operating the plackets to move 30 them apart against the tension of the spring member.

According to an important feature of my present invention, placket-operating levers are employed in combination with a combined bridge and spring member, the lenses being carried by the spring member, the 35 transverse portion of which is preferably stiffened. Also in carrying out my invention, the lens supports and the placket-operating levers, as well as also the plackets or 40 nose guards, may form extensions of such spring member which may be formed in one piece or integral therewith.

45 My invention further includes features of construction and combinations of parts as will appear from the following description.

I shall now describe the several pince-nez constructions illustrated in the accompanying drawings as embodying my invention 50 and shall thereafter point out my invention in claims.

Figure 1 is a perspective from the rear and above of a pince-nez embodying my invention, parts of the lenses being omitted,

and Fig. 2 is a plan of the same. Fig. 3 is a 55 view similar to Fig. 1 of a modified construction of which Fig. 4 is a plan. Fig. 5 is a rear elevation of a further modification of which Fig. 6 is a plan. Fig. 7 is a rear elevation and Fig. 8 a plan of another modified construction. Fig. 9 is a rear elevation and Fig. 10 a plan of yet another modification of the invention.

In all of the constructions or modifications of my invention illustrated in the accompanying drawings, a single lens-supporting and placket-carrying transversely arranged member is employed and is a spring member formed from a strip of metal which is shown as bent in its connecting portion 60 and in its spring-forming portions substantially to the shape of the capital letter C.

In the construction embodying my invention illustrated in Figs. 1 and 2, a lens-supporting and placket-carrying spring member is employed shown as formed from a flat strip of metal and having a wider and correspondingly stiffer upper slightly curved connecting portion 1 arranged transversely substantially horizontally. Reduced and 70 correspondingly more flexible end portions 2 of the spring member are horizontally curved rearwardly and inwardly so that these horizontally curved flexible spring extensions 2 of the stiffened transverse connecting portion 1 form together therewith substantially a capital letter C arranged 75 transversely. Somewhat wider downwardly turned continuations of the flexible spring ends 2 form nose-engaging plackets or 80 guards 3, as appears in the drawings. The spring member at the ends of its middle stiffened transverse portion 1 is bifurcated or split to form lens-supporting extensions 85 4 which extend slightly rearwardly downwardly and outwardly and at their ends are provided with usual clips or mounts 5 for supporting usual lenses 6. Spring-controlling placket-operating lever arms 7 are 90 shown as forming integral forward projections from the upper ends of the plackets 3, and these lever arms 7 extend forwardly and outwardly and at points intermediate of 95 their length are pivoted by means of pivot studs shown as pivot screws 8 upon lever supporting lugs 9 formed from the same 100 piece of metal as and bent over from the spring member and shown as bent out-

105

wardly and downwardly from the upper part of the lens-supports 2 adjacent to the stiffened middle portion 1 of the spring member, as appears in the drawings. The 5 front ends of the pivoted placket-operating lever arms 7 are adapted to be gripped by the fingers and pressed together for moving apart the nose-engaging plackets 3 against the tension of the spring member, which is 10 the most yielding in its curved flexible end portions 2 and but slightly yielding in its stiffened middle portion 1, as will be readily understood. The nose-engaging plackets 3 are shown as provided with usual pads or 15 plates 10 which may be of any usual or suitable material, as is understood in the art.

The modified construction illustrated in Figs. 3 and 4 differs from that just described, in reference to Figs. 1 and 2, in that the 20 placket-operating lever arms 11 project forwardly integrally with and from substantially middle points of the plackets 12 and are pivoted upon the lower horizontally outward ends of the lens-supports 13, which 25 are formed integrally with and as extensions of a horizontally curved spring member having a wider and stiffened middle portion 14 and more flexible curved end portions 15, in this respect being similar to the first 30 described construction, and the operation or manner of use is substantially the same.

In the further modified construction illustrated in Figs. 5 and 6 the lenses 16 are 35 shown as supported by means of usual metal bands or rims 17 and distance blocks or posts 18, upon the plackets 19, and are shown in the drawings as supported at the lower ends of the plackets. In this construction the plackets 19 perform a double function, serving as nose-engaging guards or 40 plackets and as lens-supporting members which take the place of the lens-supporting extensions, such as 4, illustrated in Figs. 1 and 2, or of the similar lens-supporting extensions 13 illustrated in Figs. 3 and 4. A 45 single lens-supporting and placket-carrying spring member has a wider and correspondingly stiffer middle transverse portion 20 which gradually tapers into horizontally 50 curved narrower resilient members 21 which, similarly to the two hereinbefore described constructions, are turned downwardly and widened to form the plackets 19. Placket-operating lever arms 22 extend forward integrally from the upper ends of the plackets 19 and at middle points are pivoted by 55 means of pivot studs 23, shown as rivets, upon lever-supporting lugs 24, shown as turned over rearwardly in L-shape from the lower edge of the transverse stiffened portion 20 of the spring member adjacent to the points where it merges into the resilient curved spring placket-carrying ends 21, as 60 appears in the drawings. The positioning and pivoting of the placket-operating lever 65

arms 22 is similar to that illustrated and described in reference to Figs. 1 and 2. The manner of operation in use is substantially the same as hereinbefore described, excepting that in the construction illustrated in 70 Figs. 5 and 6, the lenses 16, by reason of their being mounted upon the plackets 19, will partake of the movement of the plackets. This movement of the lenses 16 being in horizontal planes, by reason of the horizontally extending curved spring ends 21 and transverse stiffened middle spring portion 20, will generally be unobjectionable and although in some instances it might be undesirable this pince-nez illustrated in 80 Figs. 5 and 6 is recommended by its extreme simplicity of construction.

The modified construction of pince-nez illustrated in Figs. 7 and 8 resemble generally that illustrated in Figs. 1 and 2 but 85 differs therefrom in the particulars now to be noted. In the construction illustrated in Figs. 7 and 8 the lens-supports 25 at their upper ends are soldered or otherwise suitably attached to the rear face of a horizontally arranged curved spring member having a wider and stiffened central portion 26 which tapers into narrower resilient end portions 27 which are turned downwardly and widened to form plackets 28, substantially the same as in all of the hereinbefore 90 described constructions. Placket-operating lever arms 29 are shown as attached by means of rivets, and they also may be soldered or otherwise attached, to the upper 95 ends of the plackets 28, and the lever arms 29 extend forwardly and are shown as pivoted by means of pivot screws 30 to lugs 31 projecting from and which may be soldered or otherwise suitably attached to the upper 100 ends of the lens-supports 25 adjacent to the ends of the stiffened portion 26 of the spring member. It will be noted that the principal difference between this construction and that illustrated in Figs. 1 and 2 is that the lens-supports 25 and the placket-operating arms 29, as well as the lever-supporting pivot lugs 31, are made of separate pieces of metal from the spring member and are attached to such spring member, which in the 110 present construction has the stiffened transverse middle connecting portion 26 and the resilient curved ends 27 which are continued downwardly to form the plackets 28. In use the operation is substantially the same 115 as in the first described construction.

The further modified construction of my invention illustrated in Figs. 9 and 10 bears a similar relation to the construction illustrated in Figs. 3 and 4 that the construction 125 illustrated in Figs. 7 and 8 bear to the construction illustrated in Figs. 1 and 2. In the construction illustrated in Figs. 9 and 10, placket-operating lever arms 32 are pivoted upon the lower horizontal ends of lens- 130

supports 33, the inner or rear ends of the lever arms 32 being soldered or riveted, as shown, or otherwise suitably attached at points near the middle of plackets 34 which 5 form continuations of resilient horizontally curved spring ends 35 of a curved horizontally arranged spring member having a middle transverse stiffened portion 36, to the rear face of which near the ends thereof the 10 upper ends of the lens-supports 33 are soldered or otherwise securely attached, as appears in the drawings. This construction differs from that illustrated in Figs. 7 and 8, in that the placket-operating lever arms 15 32 are pivoted upon the lower horizontal ends of the lens-supports 33 and are attached to middle points of the plackets 34. The operation in use is substantially the same as that of the hereinbefore described constructions.

It is obvious that various modifications may be made in the constructions illustrated in the drawings and above particularly described within the principle and scope of my 25 invention.

I claim:

1. In a pince-nez, the combination with the lenses, of a lens-supporting spring member comprising an upper curved portion arranged 30 in a substantially horizontal plane and rearwardly and downwardly extending portions carried by the upper portion and forming plackets, and operating means carried by the spring member and adapted to 35 move the plackets apart against the action of the spring member.

2. In a pince-nez, the combination of a lens-supporting spring member comprising a portion arranged substantially horizontally and forming a bridge and rearwardly and downwardly curved end portions, plackets extending downwardly from the ends of the end portions of the spring member, and placket-operating lever arms adapted to 45 move the plackets apart against the tension of the spring member.

3. In a pince-nez, the combination of a spring member comprising a portion arranged substantially horizontally and forming a bridge, lens supports extending downwardly from the ends of the bridge portion, the spring member having rearwardly and downwardly curved end portions extending beyond the lens supports, plackets extending 50 downwardly from the ends of said end portions of the spring member, and placket-operating lever arms adapted to move the plackets apart against the tension of the spring member.

4. In a pince-nez, the combination of a spring member comprising a portion arranged substantially horizontally and forming a bridge, lens supports extending downwardly from the ends of the bridge portion, 55 the spring member having rearwardly and

downwardly curved end portions extending beyond the lens supports, plackets extending downwardly from the ends of said end portions of the spring member, and placket-operating lever arms fulcrumed on the spring member at the ends of the bridge portion thereof and connected to the upper ends of the plackets for moving the plackets apart against the tension of the spring member.

5. In a pince-nez, the combination of a lens-supporting spring member comprising a stiffened portion arranged substantially horizontally and forming a bridge and flexible rearwardly curved end portions turned downwardly, plackets extending downwardly from the downwardly turned end portions of the spring member, and placket-operating lever arms adapted to move the plackets apart against the tension of the spring member.

6. In a pince-nez, the combination of a spring member comprising a stiffened portion arranged substantially horizontally and forming a bridge, lens supports extending downwardly from the ends of the stiffened bridge portion, the spring member having flexible rearwardly curved end portions turned downwardly, plackets extending downwardly from the downwardly turned end portions of the spring member, and placket-operating lever arms fulcrumed on the spring member at the ends of the stiffened bridge portion and connected to the upper ends of the plackets for moving the plackets apart against the tension of the spring member.

7. In a pince-nez, the combination of a spring member comprising a portion arranged substantially horizontally and forming a bridge, lens supports formed in one piece with the spring member and extending downwardly from the ends of the bridge portion, the spring member having rearwardly and downwardly curved end portions extending beyond the lens supports, plackets extending downwardly from the ends of said end portions of the spring member, and placket-operating lever arms adapted to move the plackets apart against the tension of the spring member.

8. In a pince-nez, the combination of a spring member comprising a stiffened portion arranged substantially horizontally and forming a bridge, lens supports formed in one piece with the spring member and extending downwardly from the ends of the stiffened bridge portion, the spring member having flexible rearwardly and inwardly curved end portions turned downwardly, plackets formed in one piece with and extending downwardly from the downwardly turned end portions of the spring member, and placket-operating lever arms fulcrumed on the spring member at the ends of the stiffened bridge portion and connected to the up-

per ends of the plackets for moving the plackets apart against the tension of the spring member.

9. In a pince-nez, the combination of a lens-supporting spring member comprising a transverse portion forming a bridge and curved end portions, plackets extending downwardly from the ends of the curved

end portions of the spring member, and placket-operating lever arms adapted to move the plackets apart against the tension of the spring member.

In testimony whereof I have affixed my signature.

HUGO BRINKHAUS.
